C. GASTGEB

JAR CLOSURE

Filed Oct. 29, 1920

FIG. 1.

FIG. 2.

FIG. 3.

FIG. 4.

CHARLES GASTGEB
INVENTOR.

BY *William A. Cottle*

ATTORNEY.

UNITED STATES PATENT OFFICE.

CHARLES GASTGEB, OF BRIDGEVILLE, PENNSYLVANIA, ASSIGNOR OF ONE-HALF TO
GEORGE J. PICARD, JR., OF CARNEGIE, PENNSYLVANIA.

JAR CLOSURE.

Application filed October 29, 1920. Serial No. 420,548.

To all whom it may concern:

Be it known that I, CHARLES GASTGEB, a citizen of the United States of America, residing at Bridgeville, in the county of Allegheny and State of Pennsylvania, have invented certain new and useful Improvements in Jar Closures, of which the following is a specification.

The present invention relates to jar closures, and has for its object the provision of an air and fluid-tight jar closure having means for holding the porcelain lid used against rotation while the outer or metal cover is being screwed down upon the rubber washer used between the top edge of the bottle neck and the under side of the porcelain lid. A further means is provided for enabling the metal cover to exert a direct and localized pressure on the rim portion of the porcelain lid, thereby exerting a direct contact pressure on the rubber washer and forming a much better rubber closed joint than is usual in the case of the commonly used jars.

Another feature of the device is the provision of a combination pressure, and molten fluid seal, in other words a double seal jar closure having the means above described for obtaining a perfect pressure tight seal between the porcelain lid used and the top edge of the bottle neck. The above features will be more fully explained as the description proceeds herein.

In the accompanying drawings forming part of this specification, I have shown one form of the physical embodiment of my invention constructed according to the best mode I have so far devised for the practical application of the principles of my invention.

Figure 1 is a vertical section taken through a jar showing my type of closure in position thereon.

Figure 2 is a top plan view of same having a portion cut away for purposes of illustration.

Figure 3 is a bottom view of the porcelain lid used.

Figure 4 shows a plan view of the annular washers used.

In the drawings 1 indicates the metal cover, 2 is a porcelain lid of the shape shown, 3 is a rubber annular washer similar to that shown in Figure 4, 4 is also an annular but non-frictional washer such as paraffined

paper of substantial thickness and of shape shown in Figure 4.

Numerical 5 indicates a bottle or jar having a raised annular shoulder 6 forming a groove 7 around the top of the jar. The metal cover 1 is provided with a thread 8 in the ordinary way and adapted to be screwed on the complementary threads on the neck of the bottle or jar 5 in the usual fashion. 9, 9 indicate a plurality of bosses, preferably only two being required, formed in the bottle neck 10, and complementary recesses 11, 11, are made in the porcelain lid 2 for a purpose next described. It is seen that by having the porcelain lid 2 held stationary on the top of the bottle neck 10, by means of the inwardly standing bosses and recesses, 9, 9 and 11, 11, respectively, and also having a paraffine or frictionless washer 4 on the top of the porcelain lid 2, that when the metal cover 1 is screwed down on the bottle neck threads 15, that the metal cover readily slides in a rotary direction over the top of the lid 2, and in this way a much greater grip can be obtained by the cover 80 threads 8 on the bottle neck 10. The reason being that when the cover 1 is screwed around on top of the rubber washer 3 in the case of an ordinary lid the rubber washer exerts an adhering resistance to the advancement of the cover while with my invention the rubber washer does not advance in a rotary direction at all, only the cover 1 being advanced and only against a frictionless paraffine washer 4 as is readily appreciated. In this way an exceedingly tight grip is obtained by the cover 1 against the rubber washer 3 making a practically air and fluid-tight seal against the passage of fluids from within the jar.

It is also observed in this connection that as the porcelain lid is unattached to the metal lid 1 in any way that the former can be readily removed and cleaned, thus being much more sanitary than when the porcelain is attached to the metal lid in the customary way, many lids being now thrown away on account of the fluid contents of the jars getting in between the porcelain and the surface of the metal lid, and having no means of being cleaned such lids are not used again.

It is noted that in some cases the arrangement of parts may be used without the bosses 9, and recesses 11, but the use of these parts are considered almost essential to the

perfect working of the device. The lid 2 is lightened somewhat by the cut-away portion 14 being removed as shown. The use of the paraffine washer 4 enables the pressure exerted by the cover 1 to be directly transferred to the rim 16 of lid 2 thus directing the pressure directly where it is needed to depress the rubber washer 3 against the top edge 12 of the bottle neck 10 and thus obtain 10 a good effective joint between the under side of the lid rim 16 and the said edge 12 of the jar neck just mentioned.

As a second seal after the cover 1 has been screwed down with a good tight joint 15 just described, a further air-tight seal is provided by means of pouring molten paraffine, or similar viscous fluid in the groove 7 so as to completely submerge the lower edge of the cover 1, and for this purpose it is evident 20 that the top of the shoulder or rim 6 must be of sufficient height to be above the bottom edge 17 of the cover 1, so that when the fluid paraffine is poured into the groove 7 the bottom of the cover will be submerged by said 25 fluid. From which description it is seen that when both the pressure seal by means of the frictionless cover 1 and rubber washer 3, and the molten fluid seal at 18 is used that the jar is perfectly air and fluid tight, and same 30 has proven in actual use to be very efficient from a practical standpoint, as can be readily proven by inverting the jar full of preserves into water, when if there is any leakage a sizzling sound, with escape of air 35 shows instantly in the water in which the end of the jar is submerged. With my type of jar it has been shown in test of this kind to be perfectly air and fluid tight.

Another feature of interest with reference 40 to the contact of the preserve content of the jar and metal is that when the ordinary "Mason" jar is inverted that the preserves

follow along the thread grooves of the cover and thus contact the metal and leave presumably poisoned contents within the jar 45 which may not be used for months afterward, thus the contents are contaminated in a way which cannot happen in using my type of jar.

I claim:

1. In a jar closure, a jar having a threaded neck, and a plurality of inwardly standing bosses formed on said neck, an annular resilient washer on the top edge of the jar neck, a jar lid having a number of complementary recesses adapted to engage the said jar neck bosses, superimposed on said washer, an annular non-friction washer on top of said jar lid rim, and a cover having a single downwardly projecting rim engaging the threaded jar neck and compressing the rubber washer between the jar lid rim and the top edge of the jar.

2. In a jar closure, a jar having an annular groove formed around the neck of the jar, a plurality of inwardly projecting bosses formed on the jar neck, a resilient washer positioned on the top edge of the neck of the jar, a lid on top of the resilient washer, having complementary recesses engaging the jar bosses, a non-frictional washer on the top of the lid, a cover on the latter washer having a single downwardly projecting rim with means of attachment to the jar neck, and viscous means in the annular jar groove submerging the bottom edge of the cover and providing a second seal for the contents of the jar.

In testimony whereof I affix my signature.

CHARLES GASTGEB.
